(57) **CLAIM**

The ornamental design for a throttle body, as shown and described.

DESCRIPTION

FIG. 1 is a front-right elevated view of a throttle body according to an embodiment of the new design;

FIG. 2 is a front-left elevated view thereof;

FIG. 3 is a front-right depressed view thereof;

FIG. 4 is a front-left depressed view thereof;

FIG. 5 is a rear-left elevated view thereof;

FIG. 6 is a rear-right elevated view thereof;

FIG. 7 is a rear-left depressed view thereof;

FIG. 8 is a rear-right depressed view thereof;

FIG. 9 is a front plan view thereof;

FIG. 10 is a rear plan view thereof;

FIG. 11 is a right-side plan view thereof;

FIG. 12 is a left-side plan view thereof;

FIG. 13 is a top plan view thereof; and,

FIG. 14 is a bottom plan view thereof.

All broken lines of equal length shown in the drawings are for environmental purposes only and form no part of the claimed design. The broken lines of unequal length show portions of a throttle body which form no part of the claimed design.

1 Claim, 12 Drawing Sheets
